EUGENE G. REISING, OF HARTFORD, CONNECTICUT.

FIREARM.

1,227,668.

Specification of Letters Patent.

Patented May 29, 1917.

Application filed March 27, 1914. Serial No. 827,607.

To all whom it may concern:

Be it known that I, EUGENE G. REISING, a citizen of the United States, and a resident of Hartford, in the county of Hartford and State of Connecticut, have invented a new and Improved Firearm, of which the following is a specification.

My invention relates more especially to the class of firearms that are held in the hand while being fired, and an object of my invention, among others, is to provide a firearm of this class that shall be extremely simple in construction and effective in operation.

15 A firearm embodying my invention and in the construction and use of which the objects hereinabove set out, as well as others, may be attained, is illustrated in the accompanying drawings, in which—

20 Figure 1 is a view in side elevation, mostly in central section, of a firearm embodying my invention, the barrel being broken off.

Fig. 2 is a side view of my improved firearm with the grips removed, the barrel being broken off.

Fig. 3 is a view looking from the rear and partially in section on plane denoted by dotted line 3—3 of Fig. 1.

Fig. 4 is a view in horizontal section 30 through the firearm on plane denoted by dotted line 4—4 of Fig. 2 and showing the magazine catch in position to secure the magazine in place.

Fig. 5 is a fragmentary view in section on 35 the same plane as Fig. 4, the catch being shown in full lines in the position occupied when the magazine is partially removed, and in dotted lines in the position it will occupy when the magazine is fully removed.

40 Fig. 6 is a bottom view of the breech-bolt.

Fig. 7 is a front view of the magazine.

Fig. 8 is a side view of the same.

Fig. 9 is a view of the upper part of the firearm looking from the front.

45 Fig. 10 is a detail view of the magazine catch.

Fig. 11 is a fragmentary view showing the relative positions of the hammer and firing pin as the latter passes over the former.

50 In the accompanying drawings the nu-

meral 10 indicates the handle or frame of my improved firearm having at its upper forward part a recess 11 to contain the lug 12 of a receiver 13, the latter having an opening 14 for one end of the barrel 15, the latter being secured within said opening as by means of interengaging screw threaded parts. A fastening screw 16 extends through a hole in the lug 12 into a threaded recess 17 in the frame for the purpose of securing the receiver to the frame or handle. Grooves 18 are formed in the sides of the frame or handle near the upper edge thereof for the reception of lips 19 extending inwardly from the side parts 20 of a breech-bolt 21. This 65 breech-bolt has grooves 22 within which ears 23 from the handle or frame extend, a projection 24 being located within the breech-bolt between the grooves 22, which projection has an opening extending lengthwise there- 70 through within which a firing pin 25 is located. The breech bolt thus constructed is located entirely back of the barrel and receiver and, except for the engaging lips and grooves, it is located entirely above the up- 75 per edge of the frame, thus constituting the entire outer surface, and in fact the entire part, of the upper back corner of the piece, which cutout corner it nicely fits into and fills. A spring 26 seated against the bot- 80 tom of the firing pin opening 27 thrusts with one end against a shoulder on the firing pin to force it outward against the hammer 32, and the firing pin has a recess 28 within which a pin 29 is located, the pin being of 85 such size as compared with the recess as to permit the firing pin to have a limited longitudinal movement within the breech-bolt. The firing pin also has a limited lateral movement within the breech-bolt, a head 30 90 on the firing pin having a cam to engage with a cam surface 31 on the breech-bolt for the purpose of centering the firing pin or moving it laterally in one direction, a lateral movement of the firing pin in the opposite 95 direction being for a purpose to be presently explained. When the firing pin is held at the backward limit of its play in the breech-bolt this lateral movement is permitted so that when the hammer is cocked and the 100

breech-bolt moves forward the firing pin may move laterally to ride over the hammer and thus present no obstruction to the forward movement of the breech-bolt, this position of the firing pin being shown in Fig. 11 of the drawings.

An extractor 33 is located in the breech-bolt at one side thereof and it has a lip located in position to engage the flange upon a cartridge shell at one side thereof to hold it for extraction in the usual manner. As the breech-bolt moves backward, under the pressure of the gases of explosion against the cartridge shell, the head 30 of the firing pin encounters the hammer and forces it backward, said pin, however, being held by the cartridge shell at the backward limit of its movement in the breech-bolt until it encounters increased resistance, when it is forced quickly forward against the cartridge shell and snaps the latter from release of the extractor and through the opening made by the breech-bolt in its backward movement. If desired a shoulder 34, or other means for engaging the head of the firing pin may be employed, to insure the forward movement of the latter to eject the cartridge shell. In the construction of parts herein shown as the hammer is pushed backwardly by the breech bolt in its backward movement the cartridge shell will be clamped by the extractor against the end of the breech bolt, tipping movement of said shell being prevented by its engagement with the barrel, but the head of the firing pin promptly encountering the shoulder 34 after the breech-bolt has moved sufficiently to remove the shell from the barrel, said pin will be caused by such contact to move quickly forward against the shell and snap the latter from the release of the extractor, by which it is held as above described.

A hammer push bar 35 is pivotally attached to the hammer, the lower end of said bar resting against or within a recess in a step 36 seated upon a main spring 37 located in an opening in the handle as clearly shown in Fig. 1 of the drawing. The main spring rests upon a seat pressing against a stud 38 projecting from a lever detent 39 pivotally mounted on the side part of the handle. This lever, as herein shown, is in the form of a bell crank lever, the stud 38 being secured in one arm thereof and the opposite arm 41 thrusting against the under surface of a breech-bolt actuating lever 40 pivotally mounted at its lower end on the side part of the frame with its upper end extending into a recess in the under side of the breech-bolt. The levers 39 and 40 are so relatively arranged that considerable power will be required to initially move the lever 40 against the resistance of the detent at this time. That is, when the lever 39 is in its

normal position the radius of the arm 41 will be somewhat in front of the line of application of force from the lever 40 to the lever 39, or slightly in front of the "dead center." In this swinging movement of the lever 40, as the breech-bolt moves backwardly, the arm 41 moves toward the pivot of the lever 40, increasing the leverage and thus there is offered less resistance to the movement of the breech-bolt at the end of its opening movement than at the beginning. It will thus be seen that the resistance by the levers 39 and 40 to the opening of the breech-bolt is greatest, for two reasons, at the beginning of such movement, first, from the fact that the points of engagement of the two levers are nearly on a "dead center" and second, from the fact that less leverage is obtained at the beginning of the movement than afterward.

This is an important feature of my invention, the lever (39) that resists the opening movement of the breech bolt being so arranged that the force applied to the breech bolt is transmitted lengthwise of the lever between its end and pivot, so that the lever may be positioned to exert any amount of resistance, even to a positive lock, to the opening movement of the breech bolt.

The amount of resistance of the detent lever 39 to the opening movement of the breech bolt at the beginning of such movement may be regulated by means of the screw 16 that controls the position of the receiver on the frame and hence of the breech bolt that rests against it. The position of the breech bolt controls the position of the lever 40, and hence the relative dispositions of the levers 40 and 39, which latter determines the amount of resistance that will be offered by the arm 41 to the opening movement of the breech bolt.

A sear 42 is pivotally mounted within the frame in position to engage the notches in the hammer in the usual manner, the tail of the sear being engaged by a trip-pin bar 43 in the form of a loop extending on opposite sides of a magazine chamber 44 in the handle, the bar being secured to a trigger 45 by means of which the bar is forced against the sear tail to disengage the sear from the notches in the hammer in the usual manner. A spring 46 has its lower end located in a recess 47 in the handle, the upper end of the spring being formed into three members, the outer and shorter members 48 of which press against a beveled surface on the bar 43 to force it forward and upward, and the central member 49 presses against the sear tail to hold the sear normally in position to engage the notches in the hammer.

A pin 51 on the lever 40 is normally located in a recess 50 in the upper edge of the

tripping bar, this upper edge being curved as shown in Fig. 2 of the drawing, preferably on the arc of a circle having the pivot of the lever for its center. This construction causes the pin to engage the curved surface of the bar at the beginning of the backward movement of the lever, thus moving the bar downwardly and out of the path of movement of the sear tail and leaving the

10 sear free to engage the notches in the hammer when the latter is cocked. This will prevent a repeated and unintentional discharge of the firearm.

A magazine 52 is located in the magazine 15 chamber 44 and is held therein by means of a spring pressed catch 53 extending across the frame and having a point 54 arranged to engage a notch 55 in the front of the magazine. The catch 53 has a magazine groove 56

20 of curved shape formed in one side, conforming somewhat to the curved shape of the front edge of the magazine but of a width to permit movement of the catch laterally of the frame to engage and release the magazine.

25 A trigger recess 57 is formed on the opposite side of the catch to receive the trigger. These two recesses are so relatively located that when the catch is in position to retain the magazine in place the trigger recess will be in position to receive the trigger, as shown in Fig. 4, and permit it to operate the sear, from which it will be seen that the position of the magazine governs the operation of the trigger. If the catch

30 be moved to release the magazine and the latter be slightly moved from its normal position the catch will be retained against the tension of its spring 60, in the position shown in Fig. 5, from which it will be noted

35 that the trigger will rest against the catch at one side of the trigger recess and cannot be moved. If the magazine be entirely removed from its chamber then the catch will move under the force of its spring to another

40 position and the trigger will rest against it on the opposite side of the trigger recess from that above described, and the catch will thus again resist operation of the trigger. This construction prevents any operation of the

45 trigger except when the magazine is fully in place, and cause of danger from discharge of the firearm when the magazine is not in place is thus avoided.

In order to retain all of the cartridges in

50 the magazine in substantially the same relative position with respect to the opening through the barrel, or in other words, to prevent them from assuming different angular positions, by reason of their flanges, with

55 respect to the axis of the barrel, I form ribs

58 on the inside of the magazine extending

its full length, the distance between these ribs

being such as to provide a space between

which the bullets closely fit. The space

within the magazine back of these ribs is of a width greater than the diameter of the flange around the cartridge shell, so that at this end the cartridges may lie out of a plane passing through their axes, as shown in Figs. 1 and 3 of the drawing, that is, these ends of the cartridges have a staggered relation sufficient to compensate for the extra thickness caused by the flanges 59.

The head of the firing pin on that side opposite the cam extends through a slot cut into the edge of the firing pin opening in the breech-bolt. The bottom of this extension 61 is inclined slightly downward and backward so that its rear end, at least, lies below the outer surface of this part of the breech-bolt, the provision for lateral movement of the pin being sufficient to permit this extension to pass into the slot as the breech-bolt and pin pass over the hammer. As the breech bolt moves back this downwardly inclined part is held below the lower surface of the breech bolt, the hammer pressing the beveled surface on the head of the firing pin against the cam 31. This position of the extreme rear end of the firing pin in the backward movement of the breech bolt forces the hammer downward far enough to prevent it touching the breech bolt in the forward movement of the latter, and the lateral movement of the firing pin enables it to ride so easily over the hammer that the latter offers no perceptible resistance to the forward movement of the breech bolt and firing pin.

While I have shown and described herein a preferred form of mechanism embodying my invention this may be changed to a greater or lesser degree without departing from the spirit and intent of the invention.

I claim—

1. In a firearm, in combination with the breech-bolt actuating lever, a lever detent, mounts for said lever and said detent arranged to cause the detent to exert its greatest resistance to the movement of the lever when the latter is in its closed position and a separate member to return the detent to its position of rest.

2. In a firearm, in combination with a breech-bolt actuating lever, a lever detent, mounts for said lever and detent arranged to cause the detent to exert its greatest resistance to the movement of the lever when the latter is in its closed position, and to gradually reduce the resistance as the lever moves from its closed position and a separate member to return the detent to its position of rest.

3. In a firearm, in combination with a breech-bolt actuating lever, a lever detent pivotally mounted to engage the breech-bolt actuating lever at a distance from its pivot and to move toward said pivot as the breech-bolt actuating lever moves from its

- closed position and a separate member to return the detent to its position of rest.
4. In a firearm, in combination with a pivotally mounted breech-bolt actuating lever having an edge at one end to engage a breech-bolt and the opposite end arranged at an angle to said engaging edge, a pivotally mounted lever detent positioned to engage said angularly disposed end on the breech-bolt actuating lever, and to move toward the pivot of the breech-bolt actuating lever as the latter moves from its closed position and means to return the detent to its position of rest.
5. In a firearm, in combination with a pivotally mounted breech-bolt actuating lever, a pivotally mounted lever detent, said lever and detent being constructed and their pivots being disposed to cause a radial line through the arm of the detent engaging said actuating lever to pass close to but just at one side of the "dead center" point of application of power between the detent and actuating lever.
6. In a firearm, in combination with a breech-bolt actuating lever, a pivot therefor, a lever detent, a pivot therefor, and an arm on said detent arranged to engage the actuating lever at a point just off the "dead center" line of application of power by the actuating lever to the lever detent.
7. In a firearm, in combination with a slideable breech-bolt, a firing pin movable lengthwise in the breech-bolt and adapted to pass over the hammer in its backward movement, a hammer, located in the path of backward movement of the firing pin to be cocked thereby, and means to permit the firing pin to have lateral movement to pass over the hammer during the forward sliding movement of the breech-bolt.
8. In a firearm, in combination with the breech-bolt, a firing pin movable lengthwise in the breech-bolt and having a lateral movement therein and with a beveled surface to cause said lateral movement, said pin being adapted to pass over the hammer in the backward movement of the breech-bolt and a hammer located in the path of backward movement of the firing pin to be cocked thereby to move the firing pin forward in the backward movement of the breech-bolt.
9. In a firearm, in combination with a slideable breech-bolt having a recess, a firing pin movable lengthwise in the breech-bolt and having a head to enter said recess, a hammer located in the path of backward movement of the firing pin to be cocked thereby, and means to permit the firing pin to have a lateral movement to pass over said hammer during the sliding movement of the breech-bolt.
10. In a firearm, in combination with a breech-bolt having a recess with a beveled
- wall, a hammer, a firing pin movable lengthwise in the breech-bolt and having a head with a beveled surface to engage that in said recess, and means to permit the firing pin to have a lateral movement in the breech-bolt to pass over the hammer.
11. In a firearm, in combination with the breech-bolt, an extractor located thereon, a hammer, a firing pin located in the breech-bolt and positioned to pass over the hammer in the backward movement of said bolt, means for forcing the firing pin backwardly in the breech-bolt, and means upon the hammer for forcing the firing pin forward to force a shell from the hold of the extractor.
12. In a firearm, in combination with a breech-bolt, an extractor located thereon, a hammer, a firing pin located therein and adapted to pass over the hammer in the backward movement of the breech-bolt, means for forcing the firing pin backwardly, and a shoulder on the hammer to engage the firing pin to force it forward and eject a shell from the hold of the extractor before the firing pin reaches its rearward position.
13. In a firearm, in combination with a breech-bolt, a firing pin having lateral movement, located in the path of backward movement of said pin to be cocked thereby and to move said pin laterally in its forward movement, a hammer, and means for holding the firing pin in its rearward position in the breech-bolt until after the cartridge head is seated against the end of the breech bolt.
14. In a firearm, in combination with a breech-bolt, a firing pin having a lengthwise movement and also having a lateral movement in the breech-bolt to permit it to pass over the hammer during the sliding movement of the breech bolt, means for forcing the firing pin in one direction, a hammer to engage the pin in its forward position, said hammer being located in the path of backward movement of the firing pin to be cocked thereby, and means to engage the firing pin in one of its lateral positions and hold it until after the cartridge head is seated against the end of the bolt.
15. In a firearm, in combination with the frame having a recess therein, a receiver having a lug to project into said recess, and a bolt passing lengthwise through said receiver into the frame to adjustably retain the receiver in place.
16. In a firearm, in combination with the frame having a recess therein, means for securing the barrel to the frame, said means including a lug fitting within and movable lengthwise within said recess, and a bolt for adjustably securing said lug in place.
17. In a firearm, in combination with the frame having a recess therein opening to its front edge, a barrel, and means for securing the barrel in place, said means including a lug fitting said recess and a bolt extending

lengthwise through said lug and threaded into the frame.

18. In combination in a firearm including a hammer, a breech-bolt having a recess in its end opening to the side thereof and also having a cam surface, a firing pin extending into the breech-bolt and having a head with a cam shaped surface and a lug projecting into said recess and adapted to extend beyond the outer side surface of the bolt when the firing pin is in one position, and means to permit lateral movement of the firing pin to cause it to ride over the hammer in its backward movement.

19. In combination in a firearm, a breech-bolt, a firing pin extending into the breech-bolt, a hammer located in the path of backward movement of the firing pin to be cocked thereby, means for forcing the firing pin backward in the breech-bolt, the outer end of said pin passing back beyond the hammer in the backward movement of the breech bolt, means to permit the firing pin to move backward in the breech-bolt during the backward movement of the hammer, means for forcing the firing pin forward in the breech-bolt during backward movement thereof, and means to permit the firing pin to ride over the hammer during the sliding movement of the breech bolt.

20. In a firearm, in combination with the frame cut away at its upper rear edge, a breech-bolt formed with its outer surface comprising the outer surface of that part of the firearm which it occupies, said bolt being slidably mounted on the frame and having its lower edges slidably attaching it to the upper edges of said cut-away part, and the entire breech-bolt in its closed position being located back of the rear end of the barrel, and means for operating the breech-bolt.

21. In a firearm, in combination with the breech-bolt, a member pivotally mounted on a fixed pivot to oppose opening movement of the breech-bolt, said member being arranged and its pivot being so disposed that the greater part of the force applied to the breech-bolt in its opening movement is resisted by said pivot, a lever pivotally mounted on a fixed pivot with one end in engagement with the breech-bolt and its other end in engagement with said member, and means for closing the breech-bolt.

22. In a firearm, in combination with the breech-bolt, a lever mounted on a fixed pivot to oppose opening movement of the breech-bolt, said lever being arranged and its pivot so located that the greater part of the force applied to the breech-bolt in its opening movement is resisted by said pivot on a line at one side of but close to a line passing through the point of application of power to said lever and its pivot and a lever pivotally mounted on a fixed pivot with one end

in engagement with the breech-bolt and its other end in engagement with said member.

23. In a firearm, in combination with the breech bolt and its actuating lever, a lever detent pivotally mounted and arranged to receive the power transmitted through the actuating lever on a line at one side of but close to a line passing through the point of application of power to said lever and its pivot and a member to force said detent in one direction.

24. In a firearm, a breech bolt, means for actuating the breech bolt, a resisting member to offer a variable resistance to movement of said actuating means, and a separate member to oppose movement of said resisting member.

25. In combination in a firearm, a hammer, a breech bolt, a firing pin extending into the breech bolt, means for forcing the firing pin backwardly within the breech bolt and to a point back of the hammer, and means rigidly fixed upon the hammer to engage the firing pin and force it forward at a predetermined point in the backward movement of the breech bolt.

26. In combination in a firearm, a hammer, a breech bolt, a firing pin extending into the breech bolt, means for forcing the firing pin backwardly in the breech bolt to a point back of the hammer, and a shoulder rigidly fixed upon the hammer to engage the firing pin and force it forward at a predetermined point in the backward movement of the breech bolt.

27. In combination in a firearm, a hammer, a breech bolt, a firing pin located within the breech bolt and having a longitudinal and a lateral movement therein and arranged to move the hammer backward, and means to move the firing pin laterally to force the hammer below the path of travel of the breech bolt.

28. In a firearm, in combination with a slidable breech bolt, a firing pin movable lengthwise in the breech bolt and having lateral movement therein and a beveled surface, a hammer located in the path of backward movement of the firing pin to be cocked thereby, and means upon the hammer to force the firing pin forward in the breech bolt and cause said beveled surface to position the firing pin to move the hammer below the under surface of the breech bolt.

29. In combination in a firearm, a hammer, a breech bolt, an extractor to engage the rim of a cartridge shell, a firing pin extending into the breech bolt, means for forcing the firing pin backward in the breech bolt, and a shoulder upon the hammer positioned to engage the firing pin and force it forward at the time the cartridge shell is disengaged from the barrel.

30. In a firearm in combination with the

1227, 668

breech-bolt, a lever pivotally mounted on a fixed pivot to oppose opening movement of said bolt, said lever being arranged and its pivot being so disposed that the greater part of the force applied to the breech-bolt is resisted by the pivot of said member, and a member pivotally secured with one end in engagement with the breech-bolt and its other end loosely connected with said lever.

EUGENE G. REISING.
